UNITED STATES PATENT OFFICE.

STERLING H. CAMPBELL, OF ST. LOUIS, MISSOURI.

COUPLER-RELEASE RIGGING.

Application filed April 6, 1921, Serial No. 458,888.

To all whom it may concern:

Be it known that I, STERLING H. CAMPBELL, a citizen of the United States of America, residing at the city of St. Louis, 5 State of Missouri, United States of America, have invented a certain new and useful Coupler-Release Rigging, of which the following is such a full, clear, and exact description as will enable anyone skilled in 10 the art to which it appertains to make and use the same, reference being had to the accompanying drawings, forming part of this specification.

My invention relates to a coupler release 15 rigging and has for its object the construction of such a device which will be simple in form and effective in operation and which may be either applied to operating rods of the type now in use or to a specially 20 constructed operating rod.

In the accompanying drawings which illustrate some forms of devices made in accordance with my invention together with a portion of a railway car to which the 25 same is applied, Figure 1 is a top plan view, Figure 2 is an enlarged section taken on the line 2—2 of Figure 1. Figure 3 is a top plan view of the end of the operating rod and attached parts, Figure 4 is a front view 30 of the parts shown in Figure 3, Figure 5 is a side elevation of the parts shown in Figures 3 and 4. Figures 6 and 7 are a top view and vertical section, respectively, showing a modification, and Figures 8 and 9 are 35 a vertical section and top plane view, respectively, showing a still further modification.

10 indicates the end of a railway car carrying a coupler head 11 provided with 40 the usual locking pin 12 having a horizontal eye 13. 14 is an operating rod provided with a handle 15 and carried in brackets 16 and 17 respectively. The bracket 16 is formed of a strip of metal secured to the car 10 by means of rivets 18 as shown in Figure 2 and provided with a downwardly and forwardly extending bend 19 adapted to receive the rod 14. This bend 19 is preferably arranged at an angle of about 45°. 50 The rod 14 is held in position in the bend 19 by means of a cotter pin 20. Owing to the shape of the bracket 16 there will be but little pressure against the cotter pin 20 as the movement of the operating rod in lifting 55 the locking pin of the coupler will tend to move the rod forward against the closed

portion of the bend 19. The bracket 17 may be of the same form as the bracket 14 or it may be any other suitable form such as is now used.

In carrying out my invention, the forwardly projecting arm 21 of the operating rod is provided with a non-cylindrical vertical eye. In the form of my device shown in Figures 1 to 5, inclusive, this eye is formed in an integral portion 22 of the arm 21, the portion being provided by flattening the end of the rod. The opening 23 in this flattened portion 22 of the arm is of considerably greater length than width as best 70 shown in Figure 3 of the drawings. To connect the arm 21 with the coupler locking pin 12, I provide a stirrup 24 consisting of a pair of parallel bars 25 connected at their lower ends by a flattened portion 26 forming an elongated loop. Each of the bars 25 is provided at its upper end with an outwardly extending portion 27. The distance between the two bars 25 is sufficient to allow the stirrup to be passed through the eye 13 of the locking pin 12 and their outside dimension is sufficient to allow them to easily pass through the vertical eye 23 of the operating rod when in the position shown in Figure 3. In placing the arm 21 in engagement with the stirrup 24, which must be accomplished before the operating rod 14 is secured to the car 10, the rod is turned to a position at right angles to its normal or operating position 90 and inclined as shown in dotted lines in Figure 4 so that its longest dimension may be engaged with the head of the stirrup as indicated in this figure after which the rod is lowered to the horizontal and rotated 95 through an angle of 90° after which it is secured in position on the car. It will be evident that in this position the outwardly extending ends 27 forming the head of the stirrup will effectively prevent the disengagement of the stirrup from the eye 23. The elongated loop formed at the lower end of the stirrup will allow of the necessary lateral movement between the coupler and operating arm, and the necessary 100 longitudinal movement is secured by the pivotal movement of the stirrup in the eye 13 of the locking pin and in the eye 23 of the operating rod.

In Figures 6 and 7, I have shown a modification of my device in which the operating rod 21 is provided with a horizontal open-

ing 30. In this construction a casting 31 having an opening 23 therein, similar to the opening 23 hereinbefore described, is attached to the rod 21. This casting 31 is provided with a cross piece 32 adapted to engage with the upper side of the rod and a cross piece 33 adapted to engage with the lower side thereof. This distance between the cross piece 32 and 33 is sufficient to allow the flattened end of the rod 21 to pass between them in an inclined direction, after which it is swung into the position shown in Figure 7 and secured by means of a locking bolt 34 passing through the sides 15 of the casing 31 and extending under the rod 21.

In applying this form of my device it will be necessary to engage the eye 23 with the strip 24 before the casting is applied to the operating rod 21.

In Figures 8 and 9, I have shown a further modification of my device adapted to be applied to an operating rod, the arm of which is provided with a vertical opening 25 35. In this form of device a casing 36 is used having a vertical eye 23 as hereinafter described and provided with a pocket 37 adapted to receive the end of the rod 21, which rod is secured therein by means of a bolt 38 and nut 39. The bolt 38 is provided with a conical head 40 adapted to engage with the vertical eye 35 and thus center the end of the rod 21 in the pocket 37. The operation of this form of device, after it is in 35 position on the rod, is the same as that first described.

Having fully described my invention, what I claim as new and desire to secure by Letters Patent of the United States is:

1. In a device of the class described, the combination with a coupler locking pin provided with an eye, of an operating rod provided with a vertical eye, a link connecting said parts and composed of two arms passing through the rod eye and connected at their lower ends by an elongated loop engaging with the eye of the locking pin and

forming a stop for the rod, said arms being spaced apart to permit insertion of the link in the pin eye, said link having a head of greater dimension than the smallest dimension of the rod eye.

2. In a device of the class described, the combination with a coupler locking pin provided with an eye, of an operating rod 55 provided with a vertical eye and a stirrup passing through the eye of the locking pin and having its lower portion elongated to permit relative lateral motion between the pin and stirrup and to form a stop for the rod 60 both arms of said stirrup passing through the eye of the operating rod and having their upper ends bent to form a head, the relative dimensions of the rod eye and said head being such as to permit the head to 65 pass through the rod eye when the parts are cut of operative position, but not when in normal position.

3. In a device of the class described, a stirrup comprising a pair of bars spaced 70 apart throughout their length connected at their lower ends to provide an elongated loop and having their upper ends bent outwardly in the plane of the stirrup to form an enlarged head.

4. In a device of the class described, the combination with a car carrying a coupler head provided with a locking pin, of a rock shaft, and operating arm carried by said rock shaft and provided with a non-circular 80 vertical eye, and a rigid link connecting the pin and operating arm, said link having spaced arms passing through the eye of the operating arm and provided with a head adapted to pass through said eye when said arm and link are at substantially right angles to their normal position in one plane and inclined to each other in another plane but to prevent disengagement of said parts when in normal position.

In testimony whereof, I have hereunto set my hand and affixed my seal.

STERLING H. CAMPBELL. [L.S.]
